(57) **CLAIM**

The ornamental design for a lighted vehicle hitch ball, as shown and described.

DESCRIPTION

FIG. 1 is a front-side elevational view of a first embodiment for a lighted vehicle hitch ball having around the ball's horizontal diameter a plurality of lights showing my new design, the remaining side elevational views being mirror images thereof;

FIG. 2 is a top plan view thereof;

FIG. 3 is a bottom plan thereof;

FIG. 4 is a front-side elevational and partial cross-sectional view of the first embodiment taken along the lines 4—4 of FIG. 1 thereof;

FIG. 5 is a front-side elevational view of a second embodiment for a lighted vehicle hitch ball having around the ball's vertical diameter a plurality of lights showing my new design, the rear side elevational view being a mirror image thereof;

FIG. 6 is a right-side elevational view thereof, the left-side elevational view being a mirror image thereof;

FIG. 7 is a top plan view thereof;

FIG. 8 is a bottom plan view thereof; and,

FIG. 9 is a front-side elevational and partial cross-sectional view of the second embodiment taken along the lines 9—9 of FIG. 5.
